UNITED STATES PATENT OFFICE.

THOMAS J. STEARNS, OF BOSTON, MASSACHUSETTS, ASSIGNOR TO ROXBURY CARPET COMPANY, OF SAME PLACE.

DESIGN FOR CARPETS.

SPECIFICATION forming part of Design No. 11,619, dated January 27, 1880.

Application filed November 24, 1879. Term of patent 3½ years.

To all whom it may concern:

Be it known that I, THOMAS J. STEARNS, of Boston, in the county of Suffolk and State of Massachusetts, have invented a new and original Design for Carpets, of which the following is a specification.

The nature of my design is fully shown in the accompanying photographic illustration.

The design consists of a ground ornamented by a fine net-work or lace pattern of light lines, which are knotted at their intersecting points and form diamond shapes with inclosed cruciform figures, and a chintz-work of leaves and flowers distributed uniformly over the ground-work.

I claim—

The design for a carpet, consisting of a ground ornamented by intersecting knotted lines forming diamond shapes, inclosing cruciform figures in net-work or lace pattern, and a superposed chintz-work of leaves and flowers, as illustrated in the accompanying photographic view.

In testimony whereof I have signed my name to this specification, in the presence of two subscribing witnesses, this 20th day of November, 1879.

THOMAS J. STEARNS.
